UNITED STATES PATENT OFFICE.

SUTTEN H. GROFF, OF LONG BEACH, CALIFORNIA.

DIATHERMY KNIFE.

Application filed October 27, 1926. Serial No. 144,542.

My invention relates to surgical instruments for use in diathermy where electricity is employed to heat and thus destroy the tissue.

5 A purpose of my invention is the provision of a combination of an electrode and a blade by which the destruction of tissue and the removal thereof can be effected simultaneously.

10 It is also a purpose of my invention to provide a diathermy knife in which the blade is detachably secured to the electrode in order to permit the substitution of any form of blade to suit a particular operation, each blade in any instance having a relatively sharp edge and by virtue of its association with the electrode operating to concentrate the current along the cutting edge so that the tissue is severed without bleeding and with or without actual cutting, thus 20 making an ordinary diathermy operation equivalent to endotherapy.

I will describe only one form of diathermy knife embodying my invention, and will 25 then point out the novel features thereof in claims.

In the drawings:

Figure 1 is a view showing in side elevation one form of diathermy knife embodying my invention;

Figure 2 is a central longitudinal sectional view taken on the line 2—2 of Figure 1;

Figure 3 is an enlarged fragmentary view of the blade holding means of the knife shown in the preceding views;

Figure 4 is a view similar to Figure 3, showing the blade holding means in side elevation;

Figure 5 is a detail view of the knife 40 blade;

Figure 6 is a transverse sectional view taken on the line 6—6 of Figure 1.

My invention in its present embodiment comprises an electrode consisting of an 45 elongated body 15 of suitable conducting material, preferably in the form of a metal tube, one end of which is open and interiorly threaded, as indicated at 16, to provide a socket in which is adapted to be received 50 the terminal of a wire (not shown) and constituting a part of the conventional high frequency system for supplying current to the electrode. The opposite end of the body 15 is closed and terminates in a conical portion 17, the latter in turn being provided 55 with an extension 18 which is constructed

to provide means for holding the blade B thereon. The extension is formed of conducting material and comprises an elongated head 19 slotted as indicated at 20, and terminating in spaced relation to the tapered portion 17, the intervening portion 18 having a flat side 21 and an inclined shoulder 22. The blade 19, as clearly shown in Figure 5, is provided with a cutting edge 23, a beveled end 24 and a slot having a wide portion 25 and a narrow portion 26, with intervening shoulders 27. In the applied position of the blade to the head the slotted portion of the head 19 engages within the slot 20, the remainder of the head being received in the slot 25. The end 24 of the blade abuts the shoulder 22 and thus the blade is removably secured on the extension.

The blade holding means just described 75 constitutes no part of my invention, but it does illustrate one form of blade and one form of attaching means therefor and its association with the electrode and as constituting a part of my diathermy knife. It 80 is to be understood that any form of blade can be used, so long as it is provided with a relatively sharp cutting edge, and any form of means for securing the blade to the electrode, either permanently or temporarily, 85 and all without departing from the spirit and scope of my invention.

In practice, the knife is adapted to constitute one terminal of a high frequency electrical circuit, a conductor included in the 90 circuit being connected within the socket 16 as has been described, and the other terminal of the circuit being applied directly to the body of the patient, as is the usual method. The electrode or body 15 is preferably covered with a suitable insulating jacket 28 in order that the surgeon may grip the electrode in the manipulation of the blade B and without fear of short circuiting the instrument. In manipulating the 100 knife the cutting edge of the blade is caused to penetrate the tissue to be removed, and immediately upon contact of the blade with such tissue current is conducted thereto to effect sufficient heating to destroy the tissue. 105 Consequently as the blade penetrates it functions to sever the tissue so that the latter can be removed without bleeding. It is important to note that the cutting edge 23 of the blade being in contact with the tissue 110 effects a concentration of the current along such cutting edge. This effects the rapid

destruction of the tissue and with a minimum consumption of current.

Although I have herein shown and described only one form of diathermy knife embodying my invention, it is to be understood that various changes and modifications may be made without departing from the spirit of the invention, and the spirit and scope of the appended claims.

10 I claim:

1. A diathermy knife comprising an electrode, and a blade thereon having a relatively sharp cutting edge, whereby current from the electrode will be concentrated along the cutting edge and the burning of tissue effected as the blade penetrates to per-

mit the removal of the tissue without bleeding.

2. A diathermy knife comprising an electrode, and a blade detachably secured on the 20 electrode and having a relatively sharp cutting edge.

3. A diathermy knife comprising an electrode including an elongated body of conducting material having a socket therein 25 adapted for the reception of a flexible conductor, an insulating jacket for the body and a conducting extension on the body having a blade thereon, provided with a relatively sharp cutting edge.

SUTTEN H. GROFF.
